UNITED STATES PATENT OFFICE.

CHARLES W. COX, OF WINCHESTER, INDIANA.

GATE-HINGE.

1,187,506.

Specification of Letters Patent. Patented June 20, 1916.

Original application filed December 15, 1914, Serial No. 877,362. Divided and this application filed October 20, 1915. Serial No. 56,977.

To all whom it may concern:

Be it known that I, CHARLES W. COX, a citizen of the United States, residing at Winchester, in the county of Randolph and 5 State of Indiana, have invented a new and useful Gate-Hinge, of which the following is a specification.

The present invention relates to gates, and more especially to gate hinges, this application being a divisional one of the application for patent on a gate filed December 15, 1914, Serial No. 877,362.

The object of the invention is the provision of a unique mounting or means for 15 hanging the gate, whereby the gate may be adjusted vertically as a whole or bodily, and supported at various vertical positions in a substantial and efficient manner.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

30 The invention is illustrated in its preferred embodiment in the accompanying drawing, wherein:

Figure 1 is a side elevation of the improved gate. Fig. 2 is a sectional view of 35 the gate, taken on the line 2—2 of Fig. 1. Fig. 3 is a fragmental view of the gate in raised position, parts being shown in section. Fig. 4 is a cross section of the gate, taken on the line 4—4 of Fig. 1. Fig. 5 is an 40 enlarged cross sectional detail taken on the line 5—5 of Fig. 1.

The gate proper comprises a vertical series of suitably spaced or arranged horizontal rails or bars 1, and a longitudinal 45 series of suitably spaced or arranged vertical parallel stiles 2, pivoted to the rails 1, by means of rivets or other pivot elements 3.

The device for hanging or mounting the 50 gate in order to hinge the same to the gate post P, and in order to enable the gate to be adjusted vertically, embodies upper and lower hangers or bearings 4 and 5 in the form of eye bolts having their shanks engaged into or through the post P and hav-

ing their eyes or bearing portions coaxial 55 or in alinement. Telescoping tubes 6 and 7 are journaled through the bearings or hangers 4 and 5, the upper and outer tube 6 being journaled through the bearing 4, and the inner and lower tube 7 being engaged through the bearing 5. The lower 60 tube 7 is held against vertical movement by means of a suitable pin or retaining element 8 engaged through the tube 7 and engaging over and under the bearing 5. The lower 65 end of the upper tube 6 terminates short of the lower bearing 5, while the upper end of the lower tube 7 terminates within the tube 6 in the vicinity of the upper bearing 4, so that the upper tube 6 in sliding 70 through the bearing 4 and upon the lower tube 7, will be supported in a substantial 75 and vertically adjustable manner, as well as being permitted to rotate.

The lower portion of the gate is provided 80 with means embracing the tube 7 immediately below the tube 6, and to this end an eye bolt 9 has its eye 10 embracing the tube 7 at a point slightly below the lower end of the tube 6, and has its shank 11 projecting between the sections or portions of the stile 2 at that end of the gate adjacent the tubes 6 and 7. Clamping plates 12 are 85 slidably mounted upon the shank 11 of the eye bolt 9 and bear against the edges of the 90 said stile 2, and have angular ends or flanges 13 overhanging the sides of the said stile, and clamping nuts 14 are threaded upon the shank 11 and seat against the plates 12 for clamping the parts together and holding the eye bolt 9 rigidly in place, so that the said eye bolt in being slidably and rotatably engaged to the tube 7, will assist in supporting and bracing the gate.

The upper portion of the gate is provided 95 with means coöperating with the tubes 6 and 7 for supporting the gate and to this end a doubled hanger bar 15 has its bend or loop extending around the tube 6 above the bearing 4, and pivoted to the said tube, by means 100 of a rivet or pivot pin 16 engaged through the sections or side portions of the bar 15 and the tube 6. The sections or side portions of the bar 15 are pivoted to the rivet or pivot member 3 at the adjacent upper 105 corner of the gate, and are also secured together below the upper or adjacent rail 1, as at 17. One of the sections or side por-

tions of the bar 15 is extended obliquely or diagonally downward toward the free end of the gate to the next lower rail 1, as at 18, and has its free end engaging and bearing 5 slidably upon the respective rail 1, as clearly apparent by reference to Fig. 1. The upper edge of the extension 18 is provided with notches 19, whereby the portion 18 forms an inclined rack, the free end of the extension 10 or rack 18 having a depending fork 20 straddling the respective rail 1 and guiding the extension or rack 18 for sliding movement upon the rail.

As a means for supporting the free end 15 of the gate at various vertical positions with the gate either horizontal or inclined, the doubled rod 21 has terminated eyes 22 pivoted to one of the lower rivets or pivot elements 3, of the gate remote from the hinged 20 end thereof, and having its sections or side portions disposed at the opposite sides of the gate, with the bend of the rod 21 arranged adjacent the notches or teeth 19 of the rack 18 to engage the same. The rack 25 18 and rod 21 are in alinement, they being disposed obliquely or diagonally, so as to support the free end of the gate in an effective manner. The free end of the gate may be provided with any suitable latch 23 30 which is engageable with a keeper 24 carried by the post S.

The hanger bar 15 and eye bolt or hanger element 9 which are engaged to the respective end of the gate, and which are engaged 35 to the telescoping tubes 6 and 7, will support the gate in a substantial manner, and allow the same to swing toward one side or the other. It is to be noted that the eye bolt 9 being journaled upon and embracing 40 the tube 7 may swing readily below the said tube when the gate is swung, and the hanger bar 15 being pivoted or secured to the tube 6 by the rivet or pivot element 16, will cause the tube 6 to be swung with the gate within 45 the bearing 3 and upon the lower tube 7.

The doubled supporting rod 21 having its bend or bight engaged to the rack 18 of the hanger bar 15, will support the gate at the horizontal or inclined position to which it has been adjusted, and by disengaging the 50 bend of the rod 21 from the rack 18, the free end of the gate may be either raised or lowered to adjust the position of the gate as desired, and when the rod 21 is again engaged to the rack 18, the gate will be held at the newly adjusted position. It is thus possible to hold the gate either horizontal, or at an angle of inclination to suit hilly or unlevel ground, or accommodate an inclined 55 gate post. In this connection, it is to be observed, that when the free end of the gate is swung upwardly and downwardly, the hanger bar 15 being pivoted to the gate and hinge tube 6, will cause the rack to swing 60 and slide upon the respective rail 1 of the 65

gate, during the vertical swinging movement of the gate, the rack being guided upon the respective rail by means of the fork 20.

To lift or elevate the gate bodily, the same is raised in any suitable manner so that the tube 6 and eye bolt 9 carried by the gate will slide upwardly upon the tube 7, the tube 6 sliding within the upper bearing 4. The gate may then be held at the elevated position, by means of a pin 25 engaged 70 through one of the series of apertures 26 provided in the tube 7, so that the pin 25 will be disposed between the lower end of the tube 6 and the eye bolt 9, for preventing the upward as well as the downward 80 movement of the gate, but to enable the gate to swing back and forth. Thus, when the gate is elevated, it will allow small animals or farm stock to pass thereunder, whereas the larger animals will be excluded from 85 passage through the gate way, and the gate cannot be forcibly raised by the animals getting under and forcing it upward, since the pin or holding element 25 will prevent this action. The pin 25 is also preferably 90 engaged through the respective aperture 26 when the gate is in its lowermost or normal position, as seen in Fig. 1. The gate may also be swung toward either side, and to 95 this end, the free end of the gate may be moved past the striking post S, by swinging the gate vertically so that the free ends of the rails 1 are retracted sufficiently to swing past the post S, and in this event, the gate may be returned to normal position. 100

The construction of the gate and its mounting is such that the strains are taken up in a most desirable manner, to relieve the gate proper of injurious strains, and the construction and assemblage of the component parts of the device are such, as to prevent the same from being readily injured. The parts of the mounting are also protected from being clogged or otherwise impaired, and the gate will be serviceable during the winter season, as well as at other periods. The upper end of the tubular member 6 is preferably flattened and welded or otherwise secured, to close the same, and to provide an ornamental head therefor. 110

Having thus described the invention, what is claimed as new is:

1. A gate structure comprising upper and lower bearings, telescopic members having their outer and inner members journaled through the upper and lower bearings, respectively, means for securing the inner telescopic member to the lower bearing, a gate secured to and carried by the outer telescopic member, and means engageable to the inner telescopic member at various positions thereof to support the outer telescopic member. 120

2. A gate structure comprising upper and lower bearings, telescopic members having 130

their outer and inner members journaled through the upper and lower bearings, respectively, means for securing the inner telescopic member to the lower bearing, a gate 5 secured to and carried by the outer telescopic member, a hanger element carried by the gate and engaging the inner telescopic element above the lower bearing, and a supporting element engageable with the inner 10 telescopic element between the outer tele-

scopic element and said hanger element at various positions of the respective parts.

In testimony that I claim the foregoing as my own, I have hereto affixed my signature in the presence of two witnesses.

CHARLES W. COX.
